UNITED STATES PATENT OFFICE.

GEORGE BOWMAN, OF BELFAST, IRELAND, ASSIGNOR TO B. G. R. JACK COMPANY, OF BELFAST, IRELAND.

JACKING APPARATUS FOR MOTOR-CARS.

1,368,688.

Specification of Letters Patent.

Patented Feb. 15, 1921.

Application filed May 6, 1918. Serial No. 232,842.

To all whom it may concern:

Be it known that I, GEORGE BOWMAN, of Ballygomartin Road, Belfast, Ireland, a subject of the King of Great Britain and Ireland, have invented certain new and useful Improvements in Jacking Apparatus for Motor-Cars, of which the following is a specification.

This invention relates to the jacking of motor cars and it consists in providing liquid pressure jacking apparatus which can be operated by, or from, the engine, and be controlled from the driver's seat, or elsewhere, the apparatus being so constructed and arranged that one or more of the wheels of the car can, as desired, be jacked up quickly and with a minimum of labor. The liquid used may be water or oil, preferably I use oil, as it is not liable to freeze although I, hereinafter, refer to the jacks as "hydraulic" jacks.

I provide four jacks, one for each wheel and each secured to a bracket on the axle beam or casing so as to depend therefrom, the jacks being suitably connected with, and supplied with liquid under pressure from a pump adapted to receive the liquid from a tank or chamber on the car the pump being driven by cam, or other gear, from the engine shaft. A suitable drive for the pump may be obtained by providing a worm on the clutch shaft of the motor car and a worm wheel on the pump shaft, the worm wheel being so supported that it can be moved clear of the worm on the clutch shaft when the pump is not to be operated and moved into mesh with the worm on the clutch shaft when it is to be operated, a suitable foot lever, or equivalent, being provided for this purpose. This arrangement gives a cheap and effective disconnectible drive without the use of clutches and the like.

I may also employ a suitable distributing device containing ports corresponding to the number of jacks and opening into a common chamber or connecting pipe containing liquid under pressure from the pump, the outlet branch from each port being connected to its corresponding jack through suitable tubing having a flexible portion, which allows for the rise and fall of the axle.

In addition to the provision of means for operating the pump by engine power, I may provide for operating the pump by hand. Such an arrangement would be useful when

it is not convenient to start the engine before jacking up the car.

A release or return valve is provided which, when opened, allows the spent liquid to return to the tank. A strong spiral 60 spring, or equivalent together with the weight of the car, returns the ram or plunger of each jack.

An important feature of the invention is that no liquid is lost, the spent liquid being 65 returned to the source of supply.

In order that the invention may be clearly understood I have hereunto appended explanatory drawings showing, by way of illustration or example, the application of 70 my invention to a motor chassis and also showing details of the apparatus.

Figure 1 is a general diagrammatic view of a vehicle showing the disposition of the jacks, pump and liquid tank.

Fig. 2 is a longitudinal section of one of the hydraulic jacks. This view also shows the jack supporting bracket carried on the front axle beam.

Fig. 3 is a view, partly in section, of a 80 pump and pump operating gear suitable for effecting the supply of liquid under pressure to the jacks.

Fig. 4 is a plan view, corresponding to Fig. 3, of the pump and driving gear.

Fig. 5 is a sectional view taken on the line x, x, Fig. 3.

Figs. 6 and 7 are sectional and plan views of a form of distributor or controller for the supply of the liquid to any jack as required.

In the example shown in the drawings there are four jacks a, b, c, d, one for each wheel. Each jack is secured to a bracket e carried, in the case of the front wheels, on the axle beam f so as to depend therefrom. 95 Each jack comprises an outer tubular casing y and inner ram y', preferably tubular as shown at Fig. 2, and fitted with a cup leather g at its top with an end piece or shoe h at bottom. The jack casing is suitably connected with, and supplied with liquid under pressure from a pump k adapted to draw the liquid, for example, oil, from a tank l, the pump k (see Figs. 3, 4 and 5) being driven by cam, or other gear, from the engine shaft. A simple and convenient drive for the pump k is shown at Figs. 3 and 4 the drive being obtained by means of a worm m on the clutch shaft n of the motor car and a worm wheel o on the pump shaft p with 110

- universal joints p^1 and p^2 between the driving cam q and the worm wheel o . The shaft p is carried by a fork r whose stem r^1 can move vertically in a guide r^2 , the stem being capable of being raised or lowered, so that the wheel can be raised clear of the worm m when the pump h is not to operate and lowered into mesh with the worm m when it is to operate, a suitable foot lever s , or equivalent, operating against a spring s^1 , being provided for the purpose. This arrangement gives a cheap and effective drive without the use of clutches and the like. When the shaft p is lowered so that the wheels m o , intermesh, the action of the engine rotates the shafts n and p and the cam q reciprocates the pump plunger k^1 against the action of the spring k^2 which returns the plunger.
- 10 The pump draws oil from the reservoir l by the pipe k^3 and non-return valve t^3 (see Fig. 5) and then forces it, through the non-return valve t^4 , to the pipe k^4 which communicates with the jacks. t is an automatic relief valve which is loaded by a spring t^1 , the spring being adjustable to determine the pressure at which the valve shall open, by means of a screw plug t^6 . When the pressure effected by the pump exceeds the amount predetermined by the adjustment of the spring t^1 oil passes through the automatic relief valve t and is returned by the port t^2 and pipe connection to the reservoir l .
- 15 20 25 30 35 40 45 50 55 60 65 A suitable distributing device w for supplying the liquid to any jack, as required, is shown at Figs. 6 and 7 and it contains four ports w^7 corresponding to the number of jacks. The plug member w^6 can be turned so that its port w^8 may communicate with any one of the casing ports w^7 (of which there would be one for each jack) to cause same to be put in communication with the supply pipes w^2 k^4 , leading from the pump h and, at such times, all the other ports would be closed. Each supply port w^7 in the casing w^1 is connected to its corresponding jack through suitable tubing having a flexible portion which allows for the rise and fall of the axle. The spring w^{11} keeps the plug member w^6 on its seat when there is no pressure behind it. The space w^{12} between the plug member w^6 and the non-moving part w^{13} is provided to allow the liquid to press the member w^6 on to its seat and thereby prevent leakage.
- The distributor could be placed in any convenient position to the driver's hand, preferably on the dash board, and, at its center, it may have a hand lever w^5 pivoted on the top of the plug w^6 and acted on by spring w^9 . By this lever the plug distributor can be turned to open the desired port and so supply liquid under pressure to operate the desired jack. The lever is locked

and the plug held in position (to suit one of the ports w^7) by the engagement of the lever with one or other of the corresponding recesses w^{10} . When the lever w^5 is caused to engage the recess w^{14} all the ports w^7 are closed. By this arrangement the jacks can be actuated, one at a time, till all four are actuated, if it is desired to bodily lift the whole car. When it is desired to return a jack to the "out of action" or, normal position, this is done (the pump being stopped) by means of a spring u (Fig. 2) which is compressed by the liquid pressure during the lowering of the jack and which, when the plug w^6 is turned to the proper position and the release valve v is opened returns the jack to its up position and also returns the liquid from the jack to the supply tank l . For convenience the release valve v may be positioned on the return pipe w^4 leading to the tank l .

With this improved apparatus it will be seen that there is provided a closed circulating system for the liquid which operates the jacks whereby all of the spent liquid is not only preserved, but is returned to the tank to be used over and over again, and at the same time an absolute control of the system is maintained. Furthermore, the entire arrangement is simple and compact and does not in any way spoil the appearance of the motor car, and also gives the greatest possible convenience and saving in labor and time, in the jacking up of the car for tire repairs, and such like.

If desired, as indicated in dotted lines at Fig. 3, the pump plunger k^1 may be operated by the hand lever s^3 (fulcrumed at s^4) instead of by the engine.

I may provide the bottom of the jacks with ball or roller casters, or equivalent, whereby the car can be turned or wheeled when jacked up off its wheels.

Having now fully described my invention what I claim and desire to secure by Letters Patent is:—

1. A motor vehicle having a plurality of liquid operated and spring retracted jacks, a pump on the vehicle connected with the jacks and operable by the motor of the vehicle through the medium of disconnectible gears, means for connecting and disconnecting the gears, a single device under hand control for distributing liquid to any jack as desired, a source of liquid supply on the vehicle and connected with the pump, and pressure relieving means for the jacks.

2. A motor vehicle having a plurality of oil operated jacks, a reciprocating pump on the vehicle, a cam shaft, a cam on the shaft driving the pump in one direction, a spring driving the pump in the opposite direction, a worm gear on the cam shaft, means for raising and lowering the cam shaft, a worm operable by the motor of the vehicle for

driving said worm gear, an oil tank on the vehicle and connected with the pump, and pressure relieving means for the jacks.

3. A motor vehicle having a plurality of liquid operated jacks, a pump on the vehicle connected with the jacks and operable by the motor of the vehicle through the medium of foot operated disconnectible gear, means for also operating the pump by hand, 10 means for connecting and disconnecting the gear, a source of liquid supply on the vehicle and connected with the pump, and means operating automatically to relieve the fluid pressure in the jacks, said means 15 consisting of a spring controlled valve on the pump outlet.

4. A motor vehicle having a plurality of liquid operated jacks, a pump on the vehicle connected with the jacks and operable 20 by the motor of the vehicle, a source of liquid supply on the vehicle and connected with the pump, said pump having inlet and outlet valves and surmounting the outlet valve and communicating therewith a relief 25 valve with outlet in direct communication with the source of liquid supply the pump forcing liquid to a distributing device comprising a rotatable plug with axial and radial ports therein and a casing with ports 30 leading to each of the jacks.

5. A motor vehicle having a plurality of liquid operated jacks, a pump on the vehicle connected with the jacks and operable by the motor of the vehicle, a source of 35 liquid supply on the vehicle and connected

with the pump, said pump having inlet and outlet valves and surmounting the outlet valve and communicating therewith a relief valve with outlet in direct communication with the source of liquid supply the 40 pump forcing liquid to a distributing device comprising a rotatable plug with axial and radial ports therein the said plug being made in two parts the one fixed and the other movable with spring interposed between the parts and a casing with ports leading to each of the jacks.

6. A motor vehicle having a plurality of liquid operated jacks, a pump on the vehicle connected with the jacks and operable 50 by the motor of the vehicle, a source of liquid supply on the vehicle and connected with the pump, said pump having inlet and outlet valves and surmounting the outlet valve and communicating therewith a relief 55 valve with outlet in direct communication with the source of liquid supply the pump forcing liquid to a distributing device comprising a rotatable plug with axial and radial ports therein, spring and lever 60 catch means for automatically locking the plug in position and a casing with ports leading to each of the jacks.

In testimony whereof I affix my signature in presence of two witnesses.

GEORGE BOWMAN.
